UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

LOOPER FOR SEWING-MACHINES.

1,115,086.

Specification of Letters Patent. Patented Oct. 27, 1914.

Application filed December 2, 1911. Serial No. 663,643.

To all whom it may concern:

Be it known that I, JAMES R. MOFFATT, a citizen of the United States, residing at Chicago, in the county of Cook, State of Illinois, have invented certain new and useful Improvements in Loopers for Sewing-Machines, of which the following is a description, reference being had to the accompanying drawing and to the letters and figures of reference marked thereon.

respectively, upon the front face, while the intermediate section 5 of the groove is on the rear face. This intermediate section 5 is however, connected with the adjacent sections 4 and 6 by eyes 7 and 8 respectively. The course of the thread through the looper is therefore, through the rear eye 9, groove section 4, eye 7, groove section 5, eye 8, groove section 6, and out through the eye 60 10 in the point of the looper.

By referring to Figs. 2 and 4, the operation of the looper will be understood. In Fig. 2, the loopers are moving forward just entering the needle loop. In Fig. 4 65 the needles are coming down to engage the thread triangle, and it will be noted in connection with the looper 2, that by reason of the groove section 5, the thread is so guided that it will not bulge to the 70 front and run the risk of being engaged by the front needle, as the latter is coming down. In other words, this invention provides a thread guiding and shielding 75 groove, which is of special importance in multiple needle sewing machine, especially where the needles are set close together, and arranged to form independent rows of stitching at a very slight distance apart.

From the above description it will be 80 apparent that I have provided a looper construction for a multiple needle machine wherein the loopers in rear of the forward looper on the carrier are set successively 85 in advance of the looper in front thereof and each of these rearward loopers are so constructed that the looper thread is carried to the rear face of the looper at that section in each looper where the needle passes to enter its thread triangle formed 90 by the previous needle loop, the looper thread and the body of the looper. This properly shields the looper threads so as to prevent any interlocking of the needles with the looper threads of the next adjacent 95 loopers, and the loopers may be set very close together.

Having thus particularly described my invention, what I claim as new and desire to secure by Letters Patent is:

100 A looper carrier having a plurality of loopers mounted thereon, the loopers in

said groove has two sections of it, 4 and 6

rear of the forward looper being set successively with their points in advance of the looper in front thereof, each of said rearward loopers having a thread groove formed in part on the rear face thereof at the section of the looper passed by the next adjacent needle on the needle avoiding movement of the looper when said needle is en-

tering the thread triangle of its coöperating looper. 10

In testimony whereof I affix my signature, in presence of two witnesses.

JAMES R. MOFFATT.
